UNITED STATES PATENT OFFICE.

FRANCIS M. CASE, OF CLEVELAND, OHIO, ASSIGNOR TO FEDERAL PORCELAIN COMPANY, OF CAREY, OHIO, A CORPORATION OF OHIO.

TUBE-FORMING MACHINE.

Application filed December 30, 1921. Serial No. 525,905.

To all whom it may concern:

Be it known that I, FRANCIS M. CASE, a citizen of the United States, residing at Cleveland, in the county of Cuyahoga and 5 State of Ohio, have invented a certain new and useful Improvement in Tube-Forming Machines, of which the following is a specification.

It has long been the custom to use, in connection with running electric wires through partitions, porcelain insulating tubes which are inserted into apertures through non-insulating or combustible materials, through which the wires may be passed and kept out 10 of contact with the material of the partition. These tubes are formed with a head at one end, as illustrated in the drawings herein, and this head has in the past been prevailingly formed by a hand operated or controlled machine. This invention relates to 15 a machine and process for heading or forming such tubes, and has for one object the provision of a machine which largely increases the rapidity of such tube formation, 20 and which acts automatically, although under the control of an operator. An important feature of my invention is that it permits a tube forming machine to be built which is safe to operate and in which a 25 guard may be used to prevent the operator's hand from penetrating the danger zone adjacent the forming punches. I illustrate my invention more or less diagrammatically in 30 the following drawings, wherein:

Figs. 1 and 2 together form a plan view of the tube forming machine with parts in section;

Figs. 3 and 4 together form a side elevation with parts in section;

Fig. 5 is an end elevation of the operating end;

Fig. 6 is an end elevation of the pulley end;

Fig. 7 is a detailed sectional view of the rotary head and ejectors;

Fig. 8 is a section on the line 8—8 of Fig. 7;

Fig. 9 is a detail view of heading dies at the moment of head formation;

Fig. 10 is a view of the Geneva mechanism

whereby the index shaft is moved intermittently;

Figure 11 is a plan of the operating end showing the guard in place;

Fig. 12 is an end view of the operating end showing the guard in place.

Like parts are illustrated by like symbols throughout the drawings.

A is a supporting framework or housing, the base A' of which is bolted to a supporting surface by the bolts A²; removable doors A³ give access to the interior. The top of the base is surrounded by a flat ledge or rim A⁴ on which rests the housing B, secured by the bolts B', the sides of which housing are inclined as at B². One wall is perforated by the longitudinal opening B³, the purpose of which will later appear. Resting on ledges B⁴ at the top of the walls B² or otherwise suitably secured to or supported by the housing B is the upper housing C, comprising a fixed portion C', a portion C², hinged as at C³ and with a hand hold C⁴ to lift it.

The drive shaft D, which has keyed to its outer end the driving pulley D', is supported on the bearings D², with the inner of which is associated a thrust ball bearing D³. Adjacent the pulley D' is the clutch mechanism D⁴, the details of which form no part of the present invention, but which is operated through a rod D⁵ and link D⁶ from the hand lever D⁷ pivoted as at D⁸ on the housing B and provided with a handle.

Mounted on the shaft D is the cam element or cylinder E about which are the two separate cam channels E' and E², the purpose of which will appear later.

Mounted on the shaft D between the bearings D² is a pinion E³ engaging the gear E⁸ on the stub shaft E⁵ which rotates in the bearings E⁶. On the shaft E⁶ is the pinion E⁷ in mesh with the spur gear E⁹ mounted on the stub shaft E¹⁰. To the outer end of the said shaft E¹⁰ is keyed the circular stop plate F, which is cut away as at F' to permit cooperation with the star wheel F² mounted on the index shaft F³. Associated with the notched wheel is the crank F⁴ having at its end the pin F⁵ supporting the roller F⁶ in the plane of the star wheel,

which is adapted to penetrate the grooves F^7 of the star wheel. The star wheel is cut away between the arms to form circular surfaces F^8 , of the same contour as the stop plate.

Keyed on the shaft F^3 is the spider H comprising a hub H' , the disc H^2 and the wheel bearing yokes H^3 , each having two bearing perforations H^4 .

10 Adjacent the outer end of the shaft F^3 is the index head I , comprising a hub I' and the ribs I^2 , the bearing yokes I^3 , and the bearing apertures I^4 . Mounted in the apertures are the moulds I^6 secured by set screws I^7 ; which seat in grooves I^8 which are internally enlarged as at I^{10} , and open within, as at I^{11} . The index head is surrounded by a bearing I^{12} , fixed within the removable rim I^{13} .

20 Slidably mounted in the wheel H , in the apertures H^4 therein, are the ejector shafts K , the outer ends of which are free while the inner ends K' are adapted to penetrate the moulds I^6 and serve as end forming dies. The end which penetrates the mould is axially perforated as at K^2 which perforation terminates in the discharge opening K^3 toward the middle of the shaft. Secured to each pair of shafts is a yoke or knock out shoe K^5 peripherally slotted as at K^6 , and locked in position by the bolt K^7 .

To guide the yokes K^5 there is provided the peripheral guide track K^8 , which is interrupted at the ejecting point, as at K^9 , as shown in Figure 8.

35 Mounted to slide in the bearings L' is the main knock out shaft L , which is suitably fixed against rotation. The end L^2 of this shaft is adjacent the shoe K^5 and is provided with a knock out dog L^3 adapted to penetrate the slot K^6 . Mounted on the shaft L are adjacent adjustable collars L^5 which are engaged by the fork L^6 projecting upwardly from the carriage L^7 which slides on the track L^8 . Projecting downwardly from said carriage is a cam stop or roller L^9 which penetrates the cam slot E' on the cam member E .

40 Outwardly projecting from the housing B is the bracket M with an outer upwardly turned elbow M' which supports the gib plate M^2 which is provided with the opposed tracks M^3 M^4 .

45 The upper track M^2 consists in a movable bearing plate, and is provided with a plurality of set screws M^{20} to adjust the distance between it and M^4 and to compensate for wear. Sliding between these tracks is a sliding punch head M^5 in which are mounted the heading dies M^6 and punch holders M^7 . Mounted therein are the punch spindles M^8 adapted to penetrate the apertures of the moulds. The heading dies M^6 are cut away as at I^{10} to form the head of the

50 tube. The spiral springs M^{11} serve to cushion the action of the punch header to prevent undue vibration and breakage.

55 I provide a guard M^{25} which consists of a plate of roughly arcuate cross section provided with strengthening ribs M^{26} , the plate being secured to the tracks M^3 and M^4 as for example by the slotted lugs M^{27} adjacent the ends of the strengthening ribs, and the bolts M^{28} . The outer end may be open as at M^{29} while the inner end is spaced slightly from the index head and may be cut away as at M^{30} to permit the moulds carried by the index head to be rotated therethrough into position opposite the punch head.

60 The sliding punch head or carriage is actuated by the lever N pivoted as at N' to the link N^2 , which is pivoted as at N^3 to the sliding punch head M^5 . The lever N is pivoted adjacent the interior of the base of the machine as at N^4 , passing through the aperture B^2 . Mounted midway on this lever is the cam stop or roller N^6 which penetrates the cam slot E^2 on the cam element E . Overlying the bracket M is the conveyor O which may be of any suitable form and is adapted to convey away the finished tubes, as they are ejected from the moulds.

65 It will be realized that while I have shown an operative device, I do not limit myself to the specific device shown and many changes may be made in the number, shape, and disposition of parts without departing from the spirit of my invention.

70 The use and operation of my invention are as follows:

75 The main shaft is constantly rotated, through a driving pulley, from any suitable power source and constantly drives the cam element and the chain of gears which controls the star wheel or Geneva movement.

80 The index shaft is moved intermittently in response to the so called Geneva motion. The star wheel is stationary during the engagement of the circular surface of the cut out wheel with the circular segment between the arms of the star. When the cut out portion of said wheel frees the arm of the star, the crank on said wheel, with the roller at its end, engages an arm of the star and rotates it one step. This brings the full surface of the wheel again in contact with the circular segment of the star and holds it stationary.

85 The index shaft has keyed to it the index head I in which are removably mounted four pairs of moulds. At any one moment of rest between the steps of the Geneva motion, the four pairs of moulds are disposed as follows: Reading on Fig. 5, the left hand pair are in position to receive a pair of blanks, manually inserted by the operator, who slips in dried tubular blanks which have been somewhat moistened to permit the upsetting of

the head. The upper pair are idle, giving the operator a chance to catch up, if he for any reason fails to insert the blanks to fill in the moulds. When they are in position in 5 the left, the pair at the right side of the figure are in position to receive the thrust of the punch spindles, and heading elements. The pair at the bottom are in position to discharge their load upon an adjacent conveyor, 10 and the completed blanks are kicked out by the ejecting mechanism. The halt between steps in the step by step rotation of the Geneva wheel and the index shaft controlled thereby, is sufficient to permit the insertion 15 of the blanks to permit the moulding and ejecting mechanism to perform its proper reciprocation.

In line with each pair of moulds are pairs 20 of ejector stops which are slidably mounted about the disc H, keyed to the shaft F². The kick out stops therefore, rotate in unison with the moulds and are always in line therewith. They serve the double purpose of moulding the rim of the inner end of the 25 blank and of ejecting these blanks after the moulding process is completed. Each kick out stop is hollow, its end being channelled about its periphery as shown in Fig. 7. This axial aperture terminates in a centrally located slot, through which bits and scraps of 30 the blank may be ejected. Each pair of kick out stops is secured to a yoke or knock-out shoe which is peripherally slotted and controlled by a peripheral guide track adapted 35 to penetrate the slot. This track is broken away opposite the bottom position, as shown in Fig. 8.

A pair of punch spindles and head forming dies is mounted to reciprocate into and 40 out of engagement with the moulds when in the right hand position as shown in Fig. 5. As shown in Fig. 9, the head forming mould contacts the blank containing mould and forms an enlarged head, while the spindle 45 M⁸ penetrates the blank and prevents its collapse during the moulding operation and reams out a clear axial hole. The end of the kick out stop positions the blank in the mould and forms its inner end, and serves as 50 the discharge for the surplus material.

The wear on the machine and the shock to the blank is minimized by the cushioning spring, as shown in Fig. 9.

One cam slot on the main shaft controls 55 the lever which actuates the punch head carriage, and as the main shaft rotates, this lever reciprocates, drawing the punch and header against and into the moulds, and withdrawing them, during each interval of 60 rest of the index shaft. The knock out stops are normally kept in constant relation to the blanks and serve as the back stop or rear end mould, but that pair of shafts which is in the bottom position, is free 65 from the control of the peripheral track

and is engaged by the knock out dog. The other cam slot on the main shaft, controls the stop on the slide which causes the reciprocation of the knock out shaft as each pair of moulds reaches the lowest position 70 in its rotation, the knock out yoke is engaged by the knock out stop and the pair of moulds engaging knock out stops moves forward to eject the blanks. The cam action then withdraws the shaft and with it the knock out stop, since the knock out dog penetrates the slot in the yoke. The finished tubes thus ejected are projected on the lateral conveyor O and carried away. 75

In case of difficulty with the machine, 80 the operator can stop it by throwing the stop lever, the end of which is in proximity with the moulds. As the material reamed out of the blanks gathers, it may be removed through one of the removable doors in the 85 housing.

Since the operator feeds the blanks into the device at a point removed from the punch, it is obvious that this type of machine is as safe as such a machine can 90 be made, but a guard is provided which makes it absolutely impossible for the operator to get his or her hand between the punch head and the index member. The longitudinal axis of the machine makes 95 such a disposition of the parts easier, as the additional advantage of easier feed, easier ejection, and easier disposal of the ejected tubes.

1. In a tube heading machine a plurality 100 of horizontal tube receiving moulds, a rotating element in which such moulds are mounted, a horizontal tube receiving die adapted to engage such moulds and means for rotating said element about a horizontal axis to present said moulds successively to said die.

2. In a tube heading machine a plurality 105 of horizontal tube receiving moulds, a rotating element in which such moulds are mounted, a horizontal tube receiving die adapted to engage said moulds, means for rotating said element about a horizontal axis to present said moulds, and means for rotating said element about a horizontal axis to 110 present said moulds successively to said die, in a step by step rotation.

3. In a tube heading machine a plurality 115 of horizontal tube receiving moulds, a rotating element in which such moulds are mounted, a horizontal tube receiving die adapted to engage such moulds and means for rotating said element about a horizontal axis to present said moulds successively to said die, and means for reciprocating said die into and out of operative engagement with said moulds.

4. In a tube heading machine a plurality 120 of horizontal tube receiving moulds, a rotating element in which such moulds are

mounted, a horizontal tube receiving die adapted to engage such moulds and means for rotating said element about a horizontal axis to present said moulds successively to said die, in a step by step rotation, and means for reciprocating said die into and out of operative engagement with said moulds.

5. In a tube heading machine a plurality of horizontal tube receiving moulds, a rotating element in which such moulds are mounted, a horizontal tube receiving die adapted to engage such moulds and means for rotating said element about a horizontal axis to present said moulds to said die, and means for reciprocating said die into operative engagement with said moulds, said reciprocating means timed in relation to said rotation.

10. 6. In a tube heading machine a plurality of horizontal tube receiving moulds, a rotating element in which such moulds are mounted, a horizontal tube receiving die adapted to engage such moulds and means for rotating said element about a horizontal axis to present said moulds successively to said die, in a step by step rotation, and means for reciprocating said die into and out of operative engagement with said moulds, said reciprocating means timed in relation to said rotation.

15. 7. In a tube heading machine a plurality of horizontal tube receiving moulds, a rotating element in which such moulds are mounted, a die adapted to engage such moulds and means for rotating said element about a horizontal axis to present said moulds successively to said die, and means for reciprocating said die into and out of operative engagement with said moulds, said reciprocating means actuated from the same power source as said rotating means.

20. 8. In a tube heading machine a plurality of horizontal tube receiving moulds, a rotating element in which such moulds are mounted, a horizontal tube receiving die adapted to engage such moulds and means for rotating said element about a horizontal axis to present said moulds successively to said die, in a step by step rotation, and means for reciprocating said die into and out of operative engagement with said moulds, said reciprocating means actuated from the same power source as said rotating means.

25. 9. In a tube heading machine a plurality of horizontal tube receiving moulds, a rotating element in which such moulds are mounted, horizontal tube receiving dies adapted to engage such moulds and means for rotating said element about a horizontal axis to present said moulds successively to said dies, said moulds and dies arranged in a plurality of separate groups.

30. 10. In a tube heading machine a plurality of horizontal tube receiving moulds, a rotat-

ing element in which such moulds are mounted, horizontal tube receiving dies adapted to engage said moulds and means for rotating said element about a horizontal axis to present said moulds successively to said dies, in a step by step rotation, said moulds and dies arranged in a plurality of separate groups.

35. 11. In a tube heading machine a plurality of horizontal tube receiving moulds, a rotating element in which such moulds are mounted, horizontal tube receiving dies adapted to engage such moulds and means for rotating said element about a horizontal axis to present said moulds successively to said dies, and means for reciprocating said dies into and out of operative engagement with said moulds, said moulds and dies arranged in a plurality of separate groups.

40. 12. In a tube heading machine a plurality of horizontal tube receiving moulds, a rotating element in which said moulds are mounted, horizontal tube receiving dies adapted to engage such moulds and means for rotating said element about a horizontal axis to present said moulds successively to said dies, in a step by step rotation, and means for reciprocating said dies into and out of operative engagement with said moulds, said moulds and dies arranged in a plurality of separate groups.

45. 13. In a tube heading machine a plurality of horizontal tube receiving moulds, a rotating element in which such moulds are mounted, horizontal tube receiving dies adapted to engage such moulds and means for rotating said element about a horizontal axis to present said moulds successively to said dies and means for reciprocating said dies into operative engagement with said moulds, said reciprocating means timed in relation to said rotating means, said moulds and dies arranged in a plurality of separate groups.

50. 14. In a tube heading machine a plurality of horizontal tube receiving moulds, a rotating element in which such moulds are mounted, horizontal tube receiving dies adapted to engage such moulds and means for rotating said element about a horizontal axis to present said moulds successively to said dies, in a step by step rotation, and means for reciprocating said dies into and out of operative engagement with said moulds, said reciprocating means timed in relation to said rotating means, said moulds and dies arranged in a plurality of separate groups.

55. 15. In a tube heading machine a plurality of horizontal tube receiving moulds, a rotating element in which such moulds are mounted, horizontal tube receiving dies adapted to engage such moulds and means for rotating said element about a horizontal axis to present said moulds successively to said dies, and means for reciprocating said dies into and out of operative engagement with said

- 7 moulds, said reciprocating means actuated from the same power source as said rotating means, said moulds and dies arranged in a plurality of separate groups.
- 5 16. In a tube heading machine a plurality of horizontal tube receiving moulds, a rotating element in which such moulds are mounted, horizontal tube receiving dies adapted to engage such moulds and means for rotating said element about a horizontal axis to present said moulds successively to said dies, in a step by step rotation, and means for reciprocating said dies into and out of operative engagement with said moulds, said reciprocating means actuated from the same power source as said rotating means, said moulds and dies arranged in a plurality of separate groups.
- 10 17. In a tube heading machine a plurality of horizontal tube receiving moulds, a rotating element in which such moulds are mounted, horizontal tube receiving dies adapted to engage such moulds and means for rotating said element about a horizontal axis to present said moulds successively to said dies, said moulds and dies being arranged in pairs.
- 15 18. In a tube heading machine a plurality of horizontal tube receiving moulds, a rotating element in which such moulds are mounted, horizontal tube receiving dies adapted to engage such moulds and means for rotating said element about a horizontal axis to present said moulds successively to said dies, said moulds and dies being arranged in pairs.
- 20 19. In a tube heading machine a plurality of horizontal tube receiving moulds, a rotating element in which such moulds are mounted, horizontal tube receiving dies adapted to engage such moulds and means for rotating said element about a horizontal axis to present said moulds successively to said dies, in a step by step rotation, said moulds and dies being arranged in pairs.
- 25 20. In a tube heading machine a plurality of horizontal tube receiving moulds, a rotating element in which such moulds are mounted, horizontal tube receiving dies adapted to engage such moulds and means for reciprocating said dies into and out of operative engagement with said moulds, said moulds and dies being arranged in pairs.
- 30 21. In a tube heading machine a plurality of horizontal tube receiving moulds, a rotating element in which such moulds are mounted, horizontal tube receiving dies adapted to engage such moulds and means for reciprocating said dies into and out of operative engagement with said moulds, said reciprocating means actuated from the same power source as said rotating means.
- 35 22. In a tube heading machine a plurality of horizontal tube receiving moulds, a rotating element in which such moulds are mounted, horizontal tube receiving dies adapted to engage such moulds successively to said dies in a step by step rotation, and means for reciprocating said dies into and out of operative engagement with said moulds, said reciprocating means timed in relation to said rotation, said moulds and dies being arranged in pairs.
- 40 23. In a tube heading machine a plurality of horizontal tube receiving moulds, a rotating element in which such moulds are mounted, horizontal tube receiving dies adapted to engage such moulds and means for reciprocating said dies into and out of operative engagement with said moulds, said reciprocating means actuated from the same power source as said rotating means.
- 45 24. In a tube heading machine a plurality of horizontal tube receiving moulds, a rotating element in which such moulds are mounted, horizontal tube receiving dies adapted to engage such moulds and means for reciprocating said dies into and out of operative engagement with said moulds, said reciprocating means actuated from the same power source as said rotating means.
- 50 25. In a horizontal tube heading machine a plurality of open ended tube receiving moulds, a rotating element in which they are mounted and means for rotating it about a horizontal axis, opposed dies adapted to penetrate each end of said moulds.
- 55 26. In a horizontal tube heading machine a plurality of open ended tube receiving moulds, a rotating element in which they are mounted and means for rotating it about a horizontal axis, opposed dies adapted to penetrate each end of said moulds, one of said dies adapted to revolve with each of said moulds and other opposed dies being fixed in relation to said rotating means.
- 60 27. In a horizontal tube heading machine a plurality of open ended tube receiving moulds, a rotating element in which they are mounted and means for rotating it about a horizontal axis opposed dies adapted to penetrate each end of said moulds, one of said dies adapted to revolve with each of said moulds and other opposed dies being fixed in relation to said rotation, and means for reciprocating said latter dies into and

- out of operative engagement with said moulds.
28. In a tube heading machine a plurality of horizontal open ended tube receiving moulds, a rotating element in which they are mounted and means for rotating it about a horizontal axis, opposed dies adapted to penetrate each end of said moulds, said moulds and dies being arranged in groups.
- 10 29. In a tube forming machine comprising a plurality of tube receiving moulds and tube heading dies adapted to engage said moulds, means for passing said moulds successively through a filling zone, a tube forming zone and a discharging zone, each mould remaining in the filling zone for a longer period than in either of the other zones.
- 20 30. In a tube forming machine comprising a plurality of tube receiving moulds, tube heading dies adapted to engage said moulds, means for passing said moulds successively through a filling zone, a tube forming zone, and a discharging zone, by a step by step motion each mould remaining in the filling zone for a longer period than in either of the other zones.
- 25 31. In a tube heading machine comprising a plurality of tube receiving moulds, means for rotating said moulds, tube heading dies adapted to engage said moulds, means for rotating said moulds successively through a filling zone, a tube forming zone, and a discharging zone, the filling zone adapted to consume substantially as much time as the rest of the zones.
- 30 32. In a tube heading machine comprising a plurality of tube receiving moulds, means for rotating said moulds, tube heading dies adapted to engage said moulds, means for rotating said moulds successively through a filling zone, a tube forming zone, and a discharging zone in a step by step rotation, the filling zone adapted to consume substantially as much time as the rest of the zones.
- 35 33. In a tube heading machine a plurality of open ended tube receiving moulds, and a rotating element in which they are mounted, and a shaft adapted to rotate said element, opposed dies adapted to penetrate each end of said moulds, one of said dies adapted to be aligned with and to rotate with each of said moulds, and other opposed dies being fixed in relation to said rotation, and means for ejecting the finished tubes comprising means for reciprocating said former dies into and out of said moulds.
- 40 34. In a tube forming machine a plurality of horizontal open ended tube receiving moulds, arranged in groups, a rotating element in which they are mounted, and means for giving it a step by step rotation about a horizontal axis, opposed dies arranged in groups, adapted to penetrate each end of said moulds, one of said dies adapted to revolve with each of said moulds and other opposed dies being fixed in relation to said revolution, and means for ejecting the finished tubes by reciprocating said former dies into and out of said moulds.
- 45 35. In a tube forming machine a plurality of open ended tube receiving moulds, arranged in groups, a rotating element in which they are mounted, and means for giving it a step by step rotation, opposed dies arranged in groups, adapted to penetrate each end of said moulds, one of said dies adapted to revolve with each of said moulds, and other opposed dies being fixed in relation to said revolution, and means for ejecting the finished tubes by reciprocating said former dies into and out of said moulds, comprising yokes joining each group of dies, and an ejector adapted to contact said yokes to reciprocate them and force said dies forward through the moulds.
- 50 36. In a tube forming machine a plurality of open ended tube receiving moulds, arranged in groups, a rotating element in which they are mounted, and means for giving it a step by step rotation, opposed dies arranged in groups, adapted to penetrate each end of said moulds, one of said dies adapted to revolve with each of said moulds, and other dies being fixed in relation to said revolution, and means for ejecting the finished tubes by reciprocating said former dies into and out of said moulds, comprising yokes joining each group of dies, an ejector adapted to contact said yokes to reciprocate them and force said dies forward through the moulds, said yokes being held against reciprocation throughout their revolution, but being freed at a point in line with the axis of the ejector.
- 55 37. In a tube forming machine a plurality of open ended tube receiving moulds arranged in groups, a rotating element in which they are mounted, and means for giving it a step by step rotation, opposed dies arranged in groups, adapted to penetrate each end of said moulds, one of said dies adapted to revolve with each of said moulds, and other dies being fixed in relation to said revolution and means for ejecting the finished tubes comprising reciprocating yokes joining each group of dies, an ejector adapted to contact said yokes to reciprocate them and force said dies forward through the moulds, said yokes being held against reciprocation through their revolution by a peripheral track.
- 60 38. In a tube forming machine a plurality of open ended tube receiving moulds, arranged in groups, a rotating element in which they are mounted, and means for giving it a step by step rotation, opposed dies arranged in groups adapted to penetrate each end of said moulds, one of said dies adapted to revolve with each of said moulds and other opposed dies being fixed in relation to said revolution, and means for ejecting the finished tubes by reciprocating said former dies into and out of said moulds.

- moulds, other dies being fixed in relation to said revolution, and means for ejecting the finished tubes comprising reciprocating yokes joining each group of dies, an ejector 5 adapted to contact said yokes to reciprocate them and force said dies forward through the moulds, said yokes being held against reciprocation throughout their revolution, by a peripheral track, said track being cut 10 away in line with the axis of the ejector.
39. In a tube forming machine a plurality of open ended tube receiving moulds, arranged in groups, a rotating element in which they are mounted, and means for 15 giving it a step by step rotation, opposed dies arranged in groups, adapted to penetrate each end of said moulds, one of said dies adapted to revolve with each of said moulds, other dies being fixed in relation to 20 said revolution, and means for ejecting the finished tubes comprising reciprocating yokes joining each group of dies, an ejector adapted to contact said yokes to reciprocate them and force said dies forward through 25 the moulds, said yokes being held against reciprocation throughout their revolution, by a peripheral track, said track being cut away in line with the axis of the ejector, the yokes being peripherally slotted to engage 30 said tracks.
40. In a tube forming machine a plurality of open ended tube receiving moulds, arranged in groups, a rotating element in which they are mounted, and means for 35 giving it a step by step revolution, opposed dies arranged in groups adapted to penetrate each end of said moulds, one of said dies adapted to revolve with each of said moulds, other dies being fixed in relation to 40 said revolution, and means for ejecting the finished tubes comprising reciprocating yokes joining each group of dies, an ejector adapted to contact said yokes to reciprocate them and force said dies forward through 45 the moulds, said yokes being held against reciprocation throughout their revolution, by a peripheral track, said yokes being peripherally slotted to engage said tracks, the ejector element being normally in line with 50 said track, and being adapted to penetrate said slots.
41. In a tube heading machine, a plurality of open ended tube forming moulds, a rotating element in which they are mounted, and a shaft adapted to rotate it, opposed dies adapted to penetrate each end of each of the moulds, one of said dies aligned with 55 said shaft and adapted to rotate with each of said moulds, an aligning support rotating with said shaft in which said dies are 60 slidably mounted intermediate their ends.
42. In a tube heading machine, a plurality of open ended tube forming moulds, a rotating element in which they are mounted, and a shaft adapted to rotate it, opposed 65 dies adapted to penetrate each end of each of the moulds, one of said dies aligned with said shaft and adapted to rotate with each of said moulds, an aligning support rotating with said shaft, in which said dies are 70 slidably mounted intermediate their ends, the outer end of such dies adapted to be supported and aligned by the moulds.
43. In a tube forming machine, a plurality of open ended tube receiving moulds, 75 a rotating element in which they are mounted, and a shaft adapted to rotate it, opposed dies adapted to penetrate each end of each mould, one of said dies aligned with said shaft and adapted to revolve with each of said moulds, an aligning support rotating with said shaft, in which said dies are 80 slidably mounted intermediate their ends, the outer end of such dies adapted to be supported and aligned by the moulds, and means for reciprocating said dies within 85 said moulds.
44. In a tube heading machine comprising a plurality of moulds and means for rotating them in a step by step rotation, dies adapted to penetrate and rotate with said moulds, opposed dies fixed against rotation and adapted to penetrate the opposite ends of the said moulds, and means for holding said rotating dies against axial 90 movement during said penetration, and means for reciprocating said rotating dies after said penetration, to eject the completed tube.
45. In a tube heading machine comprising a plurality of open ended moulds, and means for rotating them, dies adapted to penetrate each end of said moulds, and control means for reciprocating said sets of dies comprising a unit cam element. 100
46. In a tube heading machine comprising a plurality of open ended moulds and means for rotating them, dies adapted to penetrate each end of said moulds, and control means for reciprocating said sets of dies comprising a unit cam element, having a plurality of cam slots therein. 105
47. In a tube forming machine comprising a plurality of open ended moulds, and means for revolving them dies adapted to 110 penetrate each end of said moulds, and control means for reciprocating both sets of dies comprising a unit cam drum, a plurality of cam slots therein, one set of said dies being directly actuated by one of said slots, 115 and a die reciprocating lever for the other set, being actuated by the other slot.
48. In a tube forming machine comprising a plurality of moulds and means for revolving them in a step by step revolution, dies adapted to penetrate and revolve with said moulds, opposed dies fixed against revolution and adapted to penetrate the opposite ends of the said moulds, and means for holding said revolving dies against axial 120 movement during said revolution. 125
- 65 ed, and a shaft adapted to rotate it, opposed

movement during said penetration, and means for reciprocating said revolving dies after said penetration, to eject the completed tube, and timing and control means for reciprocating both sets of dies in rotation, comprising a unit cam drum.

49. In a tube forming machine comprising a plurality of moulds and means for revolving them in a step by step revolution, dies adapted to penetrate and revolve with said moulds, opposed dies fixed against revolution and adapted to penetrate the opposite ends of the said moulds, and means for holding said revolving dies against axial movement during said penetration, means for reciprocating said revolving dies after said penetration, to eject the completed tube, and timing and control means for reciprocating both sets of dies in rotation, comprising a unit cam drum, having a plurality of cam slots therein.

50. In a tube forming machine comprising a plurality of moulds and means for revolving them in a step by step revolution, dies adapted to penetrate and revolve with said moulds, opposed dies fixed against revolution and adapted to penetrate the opposite ends of the said moulds, and means for holding said revolving dies against axial movement during said penetration, means for reciprocating said revolving dies after said penetration, to eject the completed tube, and timing and control means for reciprocating both sets of dies in rotation, comprising a unit cam drum, a plurality of cam slots therein, an ejector element directly actuated by one of said slots and a die reciprocating lever actuated by the other.

51. In a tube heading machine comprising an open ended mould, and dies adapted to penetrate either end of said mould, a die stop comprising a tube in alignment with said mould, a die stop comprising a tube in alignment with said mould and adapted to penetrate therein, and a discharge opening through the wall of said tube spaced away from said mould.

52. A tube forming machine comprising tubular moulds and dies adapted to penetrate each end thereof, one of said dies comprising a head forming element and centrally located punch spindle, the other comprising a tube having a central aperture and an outer discharge opening at a point removed from the mould.

53. A tube forming machine comprising tubular moulds and dies adapted to penetrate each end thereof, one of said dies comprising a head forming element and centrally located punch spindle, the other comprising a tube having a single aperture and an outer discharge opening at a point removed from the mould, means adapted to hold the latter dies stationary during the excursion of the former into the mould and

actuating means adapted to force the latter forward through the mould after the withdrawal of the former.

54. In a tube forming machine a plurality of tube receiving moulds, a rotating element in which such moulds are mounted, and means for rotating it on a horizontal axis, a tube forming die adapted to engage such moulds, and means for rotating said element to present said moulds successively to said die.

55. In a tube forming machine a plurality of tube receiving moulds, a rotating element in which such moulds are mounted and means for rotating it on a horizontal axis, a tube forming die adapted to engage said moulds and means for rotating said element to present said moulds successively to said die, in a step by step rotation.

56. In a tube forming machine a plurality of tube receiving moulds, a rotating element in which such moulds are mounted, and means for rotating it on a horizontal axis, a tube forming die adapted to engage such moulds and means for rotating said element to present said moulds successively to said die, and means for reciprocating said die into and out of operative engagement with said moulds.

57. In a tube forming machine a plurality of tube receiving moulds, a rotating element in which such moulds are mounted, and means for rotating it on a horizontal axis, a tube forming die adapted to engage such moulds and means for rotating said element to present said moulds successively to said die, in a step by step rotation, and means for reciprocating said die into and out of operative engagement with said moulds.

58. In a tube forming machine a plurality of tube receiving moulds, a rotating element in which such moulds are mounted, a tube forming die adapted to engage such moulds and means for rotating said element to present said moulds to said die, and means for reciprocating said die into operative engagement with said moulds, said reciprocating means timed in relation to said rotation.

59. In a tube forming machine a plurality of open ended tube receiving moulds, a rotating element in which they are mounted, and means for rotating it on a horizontal axis, opposed dies adapted to penetrate each end of said moulds.

60. In a tube heading machine a plurality of open ended tube forming moulds, a rotating element in which they are mounted, and means for rotating it on a horizontal axis, opposed dies adapted to penetrate each end of said moulds, one of said dies adapted to rotate with each of said moulds and other opposed dies being fixed in relation to said rotation.

61. In a tube heading machine comprising a plurality of tube receiving moulds, means for rotating said moulds about a horizontal axis, and tube forming dies adapted to engage said moulds, means for rotating said moulds successively through a filling zone, a tube forming zone and a discharge zone.

62. In a tube heading machine comprising a plurality of tube receiving moulds, means for rotating said moulds about a horizontal axis, tube forming dies adapted to engage said moulds, means for rotating said moulds successively through a filling zone, a tube forming zone, and a discharging zone in a step by step rotation.

63. In a tube heading machine comprising a plurality of tube receiving moulds, means for rotating said moulds about a horizontal axis, tube forming dies adapted to engage said moulds, means for rotating said moulds successively through a filling zone, a tube forming zone, and a discharging zone, the filling zone adapted to consume substantially as much time as the rest of the zones.

64. In a tube heading machine comprising a plurality of tube receiving moulds, means for rotating said moulds about a horizontal axis, tube forming dies adapted to engage said moulds, means for rotating said moulds successively through a filling zone, a tube forming zone, and a discharging zone in a step by step rotation, the filling zone adapted to consume substantially as much time as the rest of the zones.

65. In a tube heading machine a plurality of open ended tube forming moulds, and a rotating element in which they are mounted and means for rotating it on a horizontal axis, and a shaft adapted to rotate said element, opposed dies adapted to penetrate each end of said moulds, one of said dies adapted to be aligned with and to rotate with each of said moulds, and other opposed dies being fixed in relation to said rotation, and means for ejecting the finished tubes

comprising means for reciprocating said former dies into and out of said moulds.

66. In a tube heading machine a substantially horizontally disposed mould and means for passing it through successive feeding, forming, and ejecting zones.

67. A tube heading machine comprising a substantially horizontally disposed mould and means for rotating it about a horizontal axis successively through feeding, forming, and ejecting zones.

68. In a tube heading machine a substantially horizontally disposed mould and means for passing it through successive feeding, forming, and ejecting zones by a step by step motion.

69. A tube heading machine comprising a substantially horizontally disposed mould and means for rotating it about a horizontal axis successively through feeding, forming, and ejecting zones by a step by step rotation.

70. In a tube heading machine, a plurality of tube receiving moulds, a substantially horizontal rotating element in which such moulds are mounted, a tube forming die adapted to engage said moulds and means for rotating said element.

71. In a tube heading machine, a plurality of tube receiving moulds, a substantially horizontal rotating element in which such moulds are mounted, a tube forming die adapted to engage said moulds and means for giving a step by step rotation to said element, the rest period being substantially longer than the rotating period.

72. In a tube forming machine having a mould and a die adapted to be reciprocated to and from said mould, means for moving said mould into and out of opposition to the path of reciprocation of said die and a guard element adapted to entirely inclose the path of reciprocation of said die.

Signed at Cleveland, county of Cuyahoga, and State of Ohio, this 21st day of December, 1921.

FRANCIS M. CASE.
